UNITED STATES PATENT OFFICE.

CHARLES F. DINGMAN, OF JERSEY CITY, NEW JERSEY.

RAILWAY SIGNALING SYSTEM.

1,143,755.

Specification of Letters Patent.

Patented June 22, 1915.

Application filed November 7, 1913. Serial No. 799,770.

To all whom it may concern:

Be it known that I, CHARLES F. DINGMAN, a citizen of the United States, residing at Jersey City, in the county of Hudson and 5 State of New Jersey, have invented certain new and useful Improvements in Railway Signaling Systems, of which the following is a specification, reference being had to the accompanying drawings.

10 This invention relates to new and useful improvements in railway signaling systems and more particularly to an automatic train controlled system and the primary object of the invention resides in providing a system 15 of this character which fulfils all the requirements for a system of this class, as set forth by the Interstate Commerce Commission.

A further object of the invention resides 20 in providing a system for use in steam railroads in which means is provided for positively braking the train upon injury to, or disability, for any reason whatsoever, of the engineer or upon injury to or derangement 25 of the signaling system.

Still another object of the invention resides in providing a system which is simple in construction, inexpensive to manufacture, in the application of the same to use, 30 and one which will be very efficient and useful in operation.

With these and other objects in view, the invention consists in the novel features of construction, combination and arrangement 35 of parts as will be hereinafter referred to and more particularly pointed out in the specification and claims.

In the accompanying drawings forming a part of this application, Figure 1 is a diagrammatic view disclosing the signaling apparatus and circuit therefor. Fig. 2 is a similar view showing a slight modification of the signaling circuit. Fig. 3 is a diagrammatic view showing in detail the complete 45 circuit and parts in a single block of the system. Fig. 4 is a diagrammatic view showing a broken track circuit caused by the breaking of a rail. Fig. 5 is a similar view showing a complete track circuit caused by 50 the disposition of a car in a particular block of the system. Fig. 6 is a detail section showing the contactor carried on the movable object and engaged with the conductor plates. Fig. 7 is a detail section through 55 the conductor. Fig. 8 is an enlarged detail

view illustrating a puppet valve as herein embodied.

In describing my invention, I shall refer to the drawings, in which similar reference characters designate corresponding parts throughout the several views and in which 1 indicates a section of a railway track divided in its length into blocks. The rails in each of the blocks are insulated from one another, as shown at 2 and the pair of rails in each block is electrically connected together by means of the wires 3 and 4, leading respectively from said rails and connected to the battery 5. For convenience, the batteries 5 will be termed track batteries and it will be seen that through the medium of said batteries and connections leading therefrom to the tracks, the latter will be electrically energized. It will also be seen that the tracks in each block are 75 separately energized.

Arranged in each block to one side of the track rails is a relay 6 which connects through the medium of the wires 7 and 8 to the rails respectively of the preceding block. 80 Thus the current connecting the rails to one block from the battery arranged in connection with the rails thereof, will also pass through the wires 7 and 8 and relay connected thereto.

The signal circuit is arranged for coöperation directly with the relays and, to this end, a pair of parallel conductor plates 9 are provided to extend the length of each block to one side thereof. These conductor 90 plates are supported in a plane above the plane of the upper face of the rails and are held in such position by means of the supporting arms 10 which are secured to the outer ends of the ties 11 which support said 95 rails. Leading from these conductor plates in each block are the wires 12 and 13, respectively which connect with a battery 14 and in the length of the wire 12, is a pivoted switch arm 15 which forms an armature in 100 connection with the relay 6, in that particular block. It will, of course, be understood that a battery 14 which, for convenience, will be termed a signal battery, is provided in each block, from which the wires 12 and 13 extend to the conductor plates in each block. When the current in one block passes through the rails thereof and through the relay connected therewith, which is disposed 105 in the block in the rear thereof, it will be 110

seen that the switch arm 15 forming an armature for said relay will be drawn to the latter, as clearly shown in Fig. 3 of the drawings, thus causing current to pass through the wires 12 and 13 and to the conductor plates 9.

One car, preferably the end one or the locomotive, of each train which is adapted to travel over the track is provided with a 10 depending arm or the like 16, the lower end of which is curved upwardly and provided with an elliptical spring contacting member 17 which is designed to fit snugly between the conductor plates 9. This contacting 15 member is normally in engagement with the conductor plates, thus completing the circuit between said plates, signal batteries and relay in connection therewith. Arranged on the referred to car of the train, is a sole- 20 noid 18, from which lead the wires 19 and 20, engaged respectively with the semi-elliptical portions of the contacting member 9. When the last referred to circuit, between the relay, signal battery and the conductor 25 plates is complete, it will be seen that the solenoid will be energized and fulcrumed at a convenient adjacent point on the car, is a lever 21 which has a projection 22 thereon, the latter being constructed to form an armature for the solenoid. A lamp 23 displaying a white light is arranged at a point adjacent the lever 21 and the one end of said lever is provided with a red roundel 24. When the solenoid is energized and the extension 22 30 of said lever 21 is in contact with said solenoid, the lever is in such position as to dispose the red roundel thereof in a position above the lamp 23 but when said solenoid is deenergized, the lever 21 is adapted to be lowered in view of the dropping of the armature portion 22 and the red roundel at the one end of said lever is adapted to be displayed in front of the lamp 23, indicating 35 danger to the engineer or other party in charge of the signaling device. The train pipe 25 which leads to the engine at which point this signaling apparatus is preferably provided, has a conventional puppet valve 26 therein which is controlled by the opposite end 27 of the fulcrumed lever 21. When 40 said lever is in the position in which the red roundel thereof is disposed above the lamp 23, that is when the solenoid 18 is energized, the end 27 of said lever is in its lowered position against the puppet valve, retaining 45 the latter in its closed position in the train line. It must be here stated that when there is a clear track the solenoid will always be energized so that in such conditions, the 50 puppet valve will remain closed, thus retaining the brakes in their inoperative positions.

Assuming a block to be unoccupied and the block immediately ahead of the same clear, the electric current from the track battery 55 passing through the rails and the wires

leading therefrom will energize the relay and thus allow the current from the signal battery which is arranged in connection with said relay to pass to the conductor plates along the block immediately in the 70 rear of the first mentioned block. When a train enters this last mentioned block, its contactor will pick up the current from the conductor plates and carry it through the solenoid to complete the circuit there- 75 through. When the completing of such circuit attracts the armature of the solenoid to raise the one end of the lever 21, such position thereof permits the red roundel of the same to be disposed above the white light 80 and permits said white light to be disclosed. In such position of the lever 21, the puppet valve referred to in connection with the train line is retained in its closed position. This condition will be maintained as long as 85 the block immediately ahead of the block last referred to remains unoccupied. If, however, a train or car occupies the first mentioned block, the current from the track battery would be short-circuited through the 90 the wheels and axles of the train or car, thus depriving the relay connected therewith of its energy which, in turn, would open the signal battery circuit in connection with said relay. Fig. 5 clearly discloses the course 95 of the circuit under such conditions, showing the relay in connection therewith to be deenergized. When such a condition occurs, the solenoid in the train which enters the block immediately in the rear of the block 100 which is already occupied, will be deenergized, the signal battery circuit being open. By deenergizing the solenoid, the one end of the lever 21 will, obviously, be lowered and the red roundel thereon disposed over the 105 lamp 23 which, obviously, displays the red light. The red light immediately discloses to the engineer the danger ahead but does not necessitate action by said engineer, inasmuch as the lowering of the one end of the 110 lever 21 raises the opposite end thereof to permit the puppet 26 to be opened. Such opening of the puppet valve releases the air from the train line, thus causing the brakes to be applied. Thus, it will be seen that a 115 train or car may not enter a block which is already occupied and when one train enters the block immediately in the rear of a block which is already occupied, such train will be automatically stopped, thus positively pre- 120 venting accident through rear-end collisions and the like. It will also be seen that should, for any reason whatsoever, a rail be broken or a wire become broken or disconnected, a train will be automatically stopped 125 in the block immediately in the rear of the block in which the damage to the rail or wire occurred.

In Fig. 2, I have shown a slightly modified form of the invention, wherein the con- 130

ductor plates 32 are supported considerably above the rails by means of a standard 33. This standard disposes the conductor plates in a plane intermediate of the rails and in a 5 plane above the cars or trains. Under such conditions, the train or engine is provided with an upstanding arm 34 which projects from the top thereof, the outer end of the same being provided with the usual contacting member. Otherwise, this form of 10 device is identical to the form heretofore described.

It will be seen that this system which is 15 obviously a simple and efficient one, may be applied in connection with any of the existing systems or made a part of any interlocking system so as to provide connections at turn-outs, switches, crossings and the like.

20 From the foregoing, it will be seen that I have provided a simple, inexpensive and efficient means for carrying out the objects of the invention, and while I have particularly described the elements best adapted to 25 perform the functions set forth, it is obvious that various changes in form, proportion and in the minor details of construction may be resorted to without departing from the spirit or sacrificing any of the 30 principles of the invention.

Having thus described this invention, what I claim is:—

1. In combination with a vehicle provided 35 with a fluid brake system and a lamp carried by the vehicle in close proximity to the train pipe of the brake system, said train pipe being provided with an opening in communication with the atmosphere, a valve 40 for closing the opening in the pipe line, a lever pivotally supported by the vehicle intermediate its length, one extremity of said

lever being provided with a roundel adapted to overlie the lamp, the opposite extremity of the lever being adapted to engage the valve when the roundel is in an inoperative 45 position relative to the lamp for holding the valve in closed position, and electrical means under control of a normally closed circuit for maintaining the lever in an adjustment with the roundel away from 50 the lamp and with the opposite extremity of the lever in contact with the valve.

2. In combination with a vehicle provided with a fluid brake system and a lamp carried by the vehicle in close proximity to the 55 train pipe of the brake system, said train pipe being provided with an opening in communication with the atmosphere, a valve for closing the opening in the pipe line, a lever pivotally supported by the vehicle intermediate its length, one extremity of said lever being provided with a roundel adapted to overlie the lamp, the opposite extremity of the lever being adapted to engage the valve when the roundel is in an inoperative 60 position relative to the lamp for holding the valve in closed position, a solenoid operatively engaged with the lever at a point between the roundel and the pivotal connection of the lever, said solenoid being positioned above the lever, and a normally closed circuit for maintaining the core of the solenoid in retracted position whereby the roundel is maintained in an elevated position. 65

In testimony whereof I hereunto affix my signature in the presence of two witnesses.
